FURNITURE TRIM HANDLE AND THE LIKE

Dagfinn O. Amdal, Rockford, Ill., assignor to National Lock Co., Rockford, Ill., a corporation of Delaware

Application December 30, 1958, Serial No. 53,982

Term of patent 14 years

(Cl. D10—8)

Fig. 2 is a side elevational view thereof;

Fig. 3 is a top plan view thereof; and

Fig. 4 is a sectional view taken on the line 4—4 of Fig. 1 and viewed in the direction of the arrows.

The essential features of the handle reside in the portions shown in full lines.

I claim:

The ornamental design for a furniture trim handle and the like, substantially as shown and described.
